UNITED STATES PATENT OFFICE.

DEWEY EUGENE ROCKENFELDER, OF MONTPELIER, OHIO.

TUNING DEVICE.

Application filed March 23, 1925. Serial No. 17,714.

The present invention consists of improvements in radio receiving sets the principal object of which is to equip the set with a novel form of tuner which will greatly augment the selectiveness of the set and permit tuning in on a greater number of stations with more accuracy.

Other objects and advantages of the invention will be apparent and suggest themselves as the description of the accompanying drawings proceeds.

While the drawings illustrate an embodiment of the invention it is to be understood that I do not intend to limit myself to the exact detail shown and described, that various changes in the form, proportion and minor details of construction as would occur to a person skilled in the art may be resorted to without departing from the nature of the invention or the claims hereto appended.

Referring to the accompanying drawings forming a part of the invention:

Fig. 1 is a front elevational view of a radio receiving set constructed in accordance with the present invention;

Fig. 2 is a top plan view of the same showing the top of the radio cabinet removed and the tube removed from its socket;

Fig. 3 is a transverse sectional view of a radio receiving set constructed in accordance with this invention, the circuit wires being shown fragmentarily;

Fig. 4 is a detail fragmentary perspective view of one of the tuning cylinders and drums or cores showing a part of the lever by which the drum or core is operated;

Fig. 5 is a side elevational view of the condenser per se;

Fig. 6 is a sectional view of the condenser taken on line 6-6 of Fig. 5; and

Fig. 7 is a diagrammatical view of a radio receiving set constructed in accordance with this invention.

In the drawings, the cabinet of the radio receiving set is generally designated 8 and includes a base 9 having the box portion 10 of the cabinet superimposed thereon. The front end of the base projects appreciably beyond the front of the box portion of the cabinet and is provided with transversely extending channels 11 each of which merges into, at the front of the cabinet box, a shallower channel 12. The box portion of the

cabinet is of usual configuration and is equipped on its rear wall with a series of 55 binding posts 13 of standard construction. A rheostat 14 is mounted on the inner face of the cabinet and may be of usual configuration. Moreover, a tube socket 15 of standard construction is mounted on the base 9. 60 A grid leak and condenser 16, of a construction hereinafter described, are also mounted on the base in proximity to the tube 15.

Of especial importance in the present invention is a tuning mechanism consisting 65 especially of a pair of dielectric elements 17 which, in the present instance, are shown to be of cylindrical configuration and are mounted transversely in the cabinet 10 with the terminals thereof in snug engagement 70 with the inner faces of the front and rear walls of the cabinet. Each cylinder has wound around a portion of its periphery, an insulated wire 18, the convolutions of which are contiguous. It is, of course, to be 75 understood that any kind of wire desired may be employed for this purpose, but it has been found that what is known in the art as #22 D. S. C. wire is especially adapted to function in accordance with the teaching of the present invention. This wire is 80 tapped at predetermined intervals, as indicated at 19, the wires extending from the points at which they are tapped to binding posts 20 mounted on the front panel of the 85 radio cabinet and equipped with contact points on the outer face of the panel which are adapted to be impinged against by dial hands 21 operable through the medium of knobs 22. The outer cylinder and its winding, designated P, constitutes the primary coil and the inner cylinder and its winding, designated S, constitutes the secondary or 90 regenerative coil.

Slidably mounted in each of the cylinders 95 17 is a drum or core 23 which is preferably made of metal and is equipped at its forward end with an extension providing an annulus 24 which is engaged by the reduced right angled inner end 25 of a lever 26, the 100 outer end of the lever being detachably engaged by a knob 27 which is superimposed on an indicating finger 28 and secures the latter from displacement. It will be noted, upon reference to Fig. 3 of the drawings, 105 that each of the levers 26 is slidable in one

of the channels 12 and above the channel 11, the latter receiving the head of the screw which depends from the knob 27. Each of the channels 11 has a calibrated longitudinally slotted plate 29 mounted thereabove. A screw of each of the knobs 27 rides in the slot of its respective plate 29 while each of the fingers 28 is slidable over the calibrations of the plate in order that the location 10 of the drums or cores 23 will at all times be determined by the position of the fingers on the calibrations. As shown in Fig. 4 of the drawings each of the cylinders 17 is provided with a longitudinally extending slot 15 30 through which the right angled end 25 of the lever 26 is movable.

The grid leak and condenser, as shown in Figs. 2, 5 and 6, consists of a condenser base 31 upon which a pair of copper plates 33 are 20 mounted which have a mica or other insulating sheet 34 interposed therebetween. The grid leak base 36 is mounted directly on top of the uppermost copper plate. In order that the copper plates and mica sheet may be 25 held in snug engagement, four (4) wood screws extend downward through grid leak base 36 and into condenser base 31. The copper plates are electrically connected by screw posts 35 which latter extend upwardly 30 through a grid leak base 36 and also through carbonized ends 37 of an insulated strip 38 which may be made of zolenite or other suitable insulating material. The carbonized ends 37 of the strip 38 are connected 35 by a carbon thread 39. As shown to advantage in Fig. 6, the grid leak base 36 is detachably mounted on the condenser base 31. Moreover, the condenser elements 33 and 34 are secured to the lower face of the grid leak base 36 by suitable adjustable 40 means 40 mounted on posts 35.

As diagrammatically illustrated in Fig. 7 of the drawings, the circuit includes A batteries 41 and B batteries 42 connected to 45 tube 43 and rheostat 44, through wires 45 and 46 respectively. An aerial 47 is in connection with the grid leak condenser and tube 43 through the medium of the wire 48 and in connection with the oscillation transformer through medium of wire 49. The oscillation transformer, in the present instance, consists of the primary and secondary coils, the former of which leads to a ground through wire 50. The B batteries 42 55 are connected to the head phones and secondary winding by wires 51.

In use of the radio receiving set constructed in accordance with the present invention, the knobs 22 are operated in a manner well 60 known in the art in order to tap in on the coils P and S. The drums or cores 23 are urged into the cylinders of the coils by manipulation of the knobs 27 in an apparent manner so as to bring them into a position 65 concentric to the convolutions of wire 18.

The inductance of the coils is varied by the drums or cores 23 through the dielectric cylinders 17. Consequently, by advancing the drums into and retracting the same from the portion of the cylinders, around which the 70 wire 18 is convoluted, a variable induction is obtained in both the primary and secondary circuits and as a result very fine tuning is accomplished. The tapped primary and secondary keep the tube coils balanced and permit a coarse change of wave length in an apparent manner. Consequently, the variance in the induction is accomplished by movement of the drums or cores 23 through the medium of the knobs 27, independent of 75 any hook-up circuit. The position of the drums is determined by the relative positions of the fingers 28 on the calibrations of the plates 29.

It is, of course, to be understood that 80 the device is susceptible of numerous changes, within the scope of the claims here-to appended, to adapt the device for use under different conditions. It has been found practical, however, to adopt the present 85 hook-up and use the same in conjunction with the tuner above described and also the particular type of condenser and grid leak herein employed which latter provides a positive contact between the copper plates 90 and posts upon which they are secured. The grid leak may be varied by a change in the carbon thread 39.

What is claimed is:—

1. A tuning device for radio circuits, comprising a primary winding and a secondary winding arranged in inductive relation, a pair of metallic elements disposed one in operative relation to each winding, each of said metallic elements being equipped at 100 one end with an annulus, the latter having an aperture therein, levers for moving the metallic elements, one end of each of which is bent at right angles and engaged in the aperture of one of the annuli, said levers being independently operable to selectively move said metallic elements, and means for varying the inductance of each winding. 110

2. A tuning device for radio circuits, comprising a pair of inductance coils arranged in inductive relation with their axes substantially parallel to each other, a metallic element disposed within the field of each coil, each metallic element being equipped at one end with an annulus, and 115 means connected to each annulus for moving each element independently of the other with respect to said coils.

3. A tuning device for radio circuits, comprising dielectric cylinders arranged side by 120 side, a winding on each cylinder, a metallic element disposed within each cylinder, each of said metallic elements being equipped at one end with an annulus, levers for moving the metallic elements connected to the annuli 125 130

for varying each of said metallic elements with respect to said dielectric cylinders and windings.

4. A tuning device for radio circuits, comprising a pair of dielectric cylinders arranged side by side, a winding on each cylinder, a metallic cylinder disposed within each dielectric cylinder, each of said metallic cylinders being equipped at one end with an annulus, levers connected to each of the annuli for moving the metallic cylinders longitudinally of its dielectric cylinder, and means for varying the inductance of said windings.

In testimony whereof I affix my seal.

DEWEY EUGENE ROCKENFELDER.
